(57) **CLAIM**

The ornamental design for a battery container, as shown and described.

DESCRIPTION

FIG. 1 is a top, front and left perspective view of a battery container, showing my new design;

FIG. 2 is a front elevation view thereof, with the back side being a mirror image thereof;

FIG. 3 is a top plan view thereof;

FIG. 4 is a bottom plan view thereof; and,

FIG. 5 is a left side view thereof, with the right side being a mirror image thereof.

The broken-line disclosure in the views is understood to represent portions of the article in which the claimed design is embodied, but which forms no part of the claimed design.
